UNITED STATES PATENT OFFICE

1,933,879

BASKET MAKING MACHINE

Chester B. Thayer, Benton Harbor, Mich.

Application September 13, 1930, Serial No.
481,611. Renewed September 23, 1933

3 Claims. (Cl. 147—47)

The present invention relates to basket-making machines; and an object thereof is to provide in such a machine co-operating basket forms relatively rotatable to shape the baskets in circular form; and further, to provide in such a machine improved members relatively movable on anti-friction devices; and further, to provide such a machine improved in various respects hereinafter appearing.

These objects are attained by, and the invention finds preferable embodiment in, the structure and mechanism hereinafter particularly described in the body of this specification, and illustrated by the accompanying drawings forming a part hereof, in which:

Figure 1 is a front elevational view of a basket-making machine;

Figure 2 is a front elevational view, partly in axial vertical section, of a convex basket form;

Figure 3 is a front elevational view, partly in axial vertical section, of a concave basket form and connections with a fluid pressure cylinder;

Figure 4 is an end view of said concave basket form; a portion of the ring member thereof being broken away;

Figure 5 is a view in axial vertical section of a modified construction of the concave basket form shown in Figures 1 and 3;

Figure 6 is a vertical sectional view of lower parts of the machine taken on line 6—6 of Figure 1;

Figure 7 is an axial sectional view of the fluid-pressure cylinder seen in Figure 1 and connected parts taken on line 7—7 of Figure 1;

Figure 8 is a transverse sectional view of parts of the same taken on line 8—8 of Figure 7;

Figure 9 is an end view of a convex basket form with adjacent parts and showing a fragment of the basket-making material in position to be formed by the basket forms and showing pressure bars for engaging hoop-making strips;

Figure 10 is a view of pawl and ratchet mechanism for turning one of the basket forms.

Figure 11 is a radial sectional view of parts of the concave member as shown in Figure 3, much enlarged.

In these drawings is illustrated a basket-making machine of the general type shown in Patent No. 619,182 to William Jackson.

The base 1 of this machine is hollow forming a compressed fluid tank 2 which contains a pair of fluid compressing cylinders or pumps disposed side by side, one (3) of which is shown in vertical section in Figure 6, the other cylinder 4 being located on the far side thereof in said view.

These cylinders contain piston heads 6 with piston rods 7 connected thereto and to the straps 8 bearing on the eccentrics 9 on the driving shaft 10, these piston heads being provided with check valves 12 and the cylinders with opposite 60 check valves 11 through which the fluid is pumped into the tank.

On a way 13 on the base a carriage 14 is slid in opposite directions by a compressed fluid cylinder 15 supplied through a pipe 16 from the tank and controlled by a valve indicated at 17 having an operating arm 18, this cylinder containing a piston having the piston rod 19 connected to a standard 20 of the carriage. A shaft 21 rotatable in bearings 22 on the base's standard 70 24 is turned by degrees by a pawl 25 mounted on an arm 26 turnable on this shaft, this pawl engaging a ratchet wheel 27 keyed on said shaft.

A convex basket form 28, in shape a slightly-tapering truncated cone, is splined at 29 on shaft 75 21 and turns in a bearing 30 on the carriage's standard 20.

A standard 31 on the carriage 14 is spaced from standard 20 thereon and carries a compressed fluid cylinder 32 containing a piston 80 head 33 having a hollow piston rod 34 carrying a concave basket form designated generally 35.

A head 36 has an interiorly threaded portion 37 screwed on the hollow outer end of rod 34, and an exteriorly threaded portion 38 screwed into the 85 base member 39 of the concave basket form, as particularly shown in Figure 3, the base member 39 having an outwardly diverging hollow shaping portion 40. A circular boss 41 projects from the center of the base member 39 and has secured 90 thereto as by screws 42 a bearing ring 43 on which is turnably mounted a circular bottom member 44 which is held in place by a retaining flange 45 of said bearing ring.

The shaping portion 40 of the base member is 95 provided adjacent the front thereof with a plurality of angularly spaced sockets 46 in which are secured the members 47 as by screws 48; and these members 47 have concave ball-receiving sockets 49 in the inner faces thereof. A ring 100 has a circular ball-race 50 in the outer surface thereof, and is turnably mounted on ball-bearings 51 seated partially within the race and partially within the ball-receiving sockets 49.

The basket-making material comprising a plurality of radially extending thin strips 52 connected at 53 in their middles, being positioned on the support 54, and the carriage 14 with the convex basket form 28 being moved by the piston rod 19 to, and held in, the position seen in Figure 110

1, the concave basket form 35 is moved by the piston rod 34 toward convex basket form 28, thereby bending the said material over form 28 and inside form 35 to form it into basket shape. 5 The carriage 14 is now slid by piston rod 19 toward the left hand side of Figure 1 carrying the forms to a position beneath a staple driving mechanism designated generally 55 of common form, (such, for instance, as is shown in said Jackson 10 patent) comprising the pitman 56 connected to the crank 57 on a driving shaft 58 and carrying at the lower end staple driving plungers in the staple chutes 59 mounted on the head 60 of the base's standard 24. This stapling mechanism 15 operates through an opening 103 in the top of the concave form.

The machine is driven by shaft 10, as by a belt carried by its pulley 61, and a belt carried by pulley 62 on said shaft and pulley 63 on shaft 58 20 operates the staple driving mechanism, and through the connecting rod 64 pivoted to the crank 65 of shaft 58 and to the ratchet mechanism's arm 26 turns the shaft 21 step by step.

By this operation the convex form 28, and the 25 ring and bottom members 100 and 44 respectively of the concave form 35 turn together carrying the basket forming material with them; and the head 36 is held from turning by a rod 66 30 slidable in bearings 67 on the carriage's arm 31. A shaft 68 is turnably mounted in a bearing 69 on upright 24 and carries blocks 70 tight thereon.

These blocks carry pressure bars 71. When the 35 pedal 72 swingably mounted at 73 on the base 1 and counter-weighted at 74 is pressed down, its rod 75 swings the bell crank lever 76 causing rod 77, pivoted thereto and to an arm 78 of one of said blocks, to turn shaft 68 and these blocks and raise the bars 71 from form 28 so that hoop-forming strips 79 may be inserted between the free 40 ends of the bars and the bent over strips 52 of the basket-making material.

The pedal being released the hoop-strips 79 are fed circularly by the rotation of form 28 into 45 positions to be stapled by the mechanism 55 to the strips 52 of said material.

When the basket has been thus formed, the carriage 14 is again moved to the position seen in Figure 1 and the basket is removed from the machine. A lever 80 and its rod 81 serve to operate 50 a clutch indicated at 82 whereby the pulley 62 is rotatably connected to and released from the driving shaft 10; and a lever 83 and its connecting rod 84 having an upwardly extending member 85 pivoted to the forwardly extending arm 18 of valve 17 serves to open and close this valve.

The pipe 86 comprising a flexible portion 87 leads from the compressed fluid tank 2 to the cylinder 32.

In the modification of the concave basket form

shown in Figure 5, the shaping side portion 40 of the base member 39 is eliminated and replaced by a plurality of angularly spaced arms 88 secured to the edge of the base member 39¹ as by screws 89. These arms have near their outer ends ball-receiving sockets 49¹ which function the same as the sockets 49 shown in Figure 3. Figure 5 also illustrates a method of mounting the bottom plate 44¹ on ball-bearings 92, which are disposed within complementary circular races 93 on the bottom plate and 94 on an auxiliary plate 95 secured to the base member.

In order that the bottom of the basket may be forced slightly into the concave opening 96 in the bottom of the convex form 28, a plunger 97 is 90 slidably secured within the tubular shaft 34 and has an outer end extending through the base member 39 and the bearing ring 43. The inner end of the plunger slides through a central opening in a plug 98 which is secured within the tubular shaft by a pin 99, having a slot 105 through which the pin 99 is diametrically inserted. The plunger 97 is normally urged outwardly by the pressure of a spring 106 located within shaft 34 and bearing against the plug 98 and a collar 107 secured on the plunger.

The invention being intended to be pointed out in the claims is not to be limited to, or by, details of construction of any particular embodiment thereof illustrated by the drawings or hereinbefore described.

What is claimed is:

1. In a basket-making machine, a basket form comprising a base, a ring spaced outwardly from the base, spaced arms connecting the ring and base, ball bearings between and in engagement with the said ring and arms, and a bottom disposed within the arms and between the ring and base and rotatably mounted upon the latter.

2. In a basket-making machine, a basket form comprising a base, a ring spaced outwardly from the base, spaced arms connecting the ring and base, ball bearings between the said ring and arms, a bottom disposed within the arms and between the ring and base and rotatably mounted upon the latter, an auxiliary plate mounted upon the base, and ball bearings between the peripheral portions of the bottom and auxiliary plate.

3. In a basket-making machine, a basket form comprising a base, a ring spaced outwardly from the base, means connecting the ring and base, anti-friction bearings between the ring and said means, a bottom disposed within the said connecting means and between the ring and base and rotatably mounted upon the latter, and an auxiliary plate in spaced relation with respect to said bottom arranged between the base and the bottom.
